E. A. DEWALD

JAR CLOSURE

Filed July 17, 1924

UNITED STATES PATENT OFFICE.

EDWARD A. DEWALD, OF MASSILLON, OHIO.

JAR CLOSURE.

Application filed July 17, 1924. Serial No. 726,543.

This invention relates to jars such as are used for canning fruit and vegetables, and more particularly to a new type of closure for such jars.

5 In my copending applications Serial No. 712,694, filed May 12, 1924, and No. 715,078, filed May 22, 1924, I have disclosed a construction of jar closure over which the present invention is an improvement. The inventions disclosed in my copending applications each include a yoke carrying one or two rotatable balls arranged to engage the lid of the jar to press the same tightly upon the mouth of the jar.

15 In the former application a single ball is carried by the yoke, giving a single point of contact between the yoke and substantially the center of the jar lid, while the yoke has a two point contact with the flanged neck 20 of the jar. Such a construction exerts an equal pressure downward upon all portions of the jar lid and effects a perfect seal, but the point of contact is at the center of the lid, making it necessary to strengthen 25 the lid at this point to obviate the danger of the same being broken or crushed by the pressure.

30 In the latter application two rotatable balls are carried by the yoke arranged to engage the lid at diametrically opposite points near the edge of the lid, the yoke having a two point contact with the flanged neck 35 of the jar. This construction overcomes the above objection, as all of the pressure is transmitted from the yoke to the lid at points substantially above the joint between the jar mouth and lid, and such a construction is satisfactory where there is no variation 40 in the size of the rotatable balls or in the relative thickness of all parts of the rubber packing ring.

45 However, it is very difficult to obtain balls, such as are used for this purpose, of a uniform size, and experience has proven that the usual jar rubbers or packing rings, at present in general use, vary in thickness as much as .020" of an inch throughout their length, that is, a ring may be .020" of an inch thicker upon one side than it is upon 50 the diametrically opposite side. These discrepancies in the rotatable balls and packing rings make it very difficult to obtain a perfect seal between the jar mouth and lid, as with the four point contact the pressure 55 is not distributed uniformly over the entire

lid, but it frequently happens that the lid may be sealed tightly at one side and still permit leakage at the other side.

The object of the present improvement is to provide a jar closure which will assure 60 a perfect air tight seal between the lid and the mouth of the jar around the entire joint.

The above and other objects are accomplished by providing a pair of diametrically 65 opposed inclined flanges around the neck of the jar, each flange preferably terminating at its lower end in a depending projection; a flanged lid being arranged to extend into the mouth of the jar and to compress the standard rubber packing ring between the flange 70 of the lid and the rim of the mouth.

The lid is provided with an annular groove in its top face near the periphery, adapted to receive a pair of substantially 75 half round knobs formed upon a rocker carried in a metal yoke, which is provided with inclined feet for contact with the inclined under sides of the flanges upon the jar neck.

80 This provides for a three point contact between the rocker and the yoke, permitting the rocker to adjust itself to accommodate any unevenness in the thickness of the standard packing ring, while a three point contact 85 is also provided between the yoke and the flanged neck of the jar, thus distributing the pressure evenly upon the jar lid, and producing an air tight seal between the same and the rim of the jar mouth.

90 An embodiment of the invention thus described in general terms is illustrated in the accompanying drawing, in which—

95 Figure 1 is a vertical sectional view of a jar provided with the improved closure;

Fig. 2, a side elevation of the upper portion of the jar;

Fig. 3, a plan view of the jar;

Fig. 4, a plan view of the lid;

Fig. 5, a bottom plan view of the yoke;

Fig. 6, a cross sectional view of the yoke;

Fig. 7, a plan view of the rocker;

Fig. 8, a side elevation of the same, and

Fig. 9, a transverse section on the line 9—9, Fig. 8.

100 Similar numerals refer to corresponding parts throughout the drawing.

The improved jar is illustrated at 1, and is provided with the reduced neck 2, around which are located diametrically opposed, in- 105

clined peripheral flanges 3, the neck terminating in an annular rim 4 surrounding the mouth 5.

The upper end of each of the inclined flanges 3 is preferably tapered, as shown at 6, the lower end terminating in the depending projection 7.

The present jar closure includes the lid 8, which is preferably molded glass, having the 10 annular flange portion 9 arranged to receive the standard rubber packing ring 10. The central portion 11 of the lid is adapted to extend into the mouth of the jar to prevent an air space between the contents of the jar 15 and the lid; and for sealing the jar the usual standard packing ring 10 is stretched around this central portion of the jar, forming a seal between the lid flange and the rim of the jar.

20 A concentric annular groove 13 is formed in the top of the lid 8, near the periphery thereof, and for the purpose of reducing the weight of the lid, the under side thereof may be cut away as shown at 14.

25 As illustrated in Fig. 1, the flange 9 of the lid projects beyond the rim of the jar mouth, permitting the entrance of a knife, or similar tool, between the lid and the adjacent flange 3, which acts as a fulcrum for 30 the knife in prying the lid from the jar.

For the purpose of clamping the lid on the neck of the jar, a U-shaped yoke 15, preferably stamped from a strip of open hearth drawn steel, is provided. This yoke 35 comprises the central channel portion 16, and the depending leg portions 17, which are preferably of greater width at their lower ends and provided with the inclined L-flanges 18, which are preferably concaved as shown, 40 and adapted to engage and operate under the inclined, annular flanges 3 upon the jar neck.

The concaved inner edges of the L-flanges 45 18 will assist in quickly centering the yoke upon the jar neck, and will prevent sidewise displacement of the yoke after it has been positioned upon the jar.

In order to strengthen the legs 17 of the yoke, a rib 21 is formed in each leg, merging into the central portion of the yoke at its 50 upper end and terminating in the lower curved end 22, extended beneath the inclined flange 18.

The rocker 23 may be of cross sectional 55 channel shape, each side flange 24 thereof having its upper or free edge constituting a slight curve as shown at 25. This rocker is loosely mounted within the channel body portion of the yoke, the projections 26 upon the legs of the yoke retaining the rocker against removal but permitting free movement of the rocker within the channel body portion of the yoke, the curved upper edge of the rocker engaging the flat top wall of the yoke.

55 A half round knob 27 is formed on the

underside of the rocker member, near each end thereof, and arranged to be received in the annular groove 13 of the lid, as shown in Fig. 1.

In placing the closure upon the jar, the 70 standard rubber ring 10 is first stretched over the central portion 11 of the lid, and the lid is then placed over the mouth of the jar, as shown in Fig. 1, the rubber packing ring being located between the annular flange 9 75 of the lid and the rim 4 of the jar mouth. The yoke is then slipped vertically over the neck of the jar, the legs thereof being received in the cut out portions 29 between the ends of the flanges 3, knobs 27, upon the 80 rocker, being received in the annular groove 13 of the lid.

The yoke is then rotated around the neck of the jar, being turned toward the right, 85 the L-flanges 18 thereof engaging and operating under the inclined lower faces of the annular flanges 3 of the jar. As the yoke is rotated, the knobs 27, upon the rocker, will travel around the annular groove 13 of the lid, preventing rotary movement of the lid 90 with relation to the jar, and permitting the lid to remain stationary upon the jar.

As the L-flanges 18 are moved toward the lower ends of the annular flanges 3, the lid will be tightly clamped upon the mouth of 95 the jar, compressing the rubber packing ring between the flange of the lid and the rim of the jar, and forming an air tight seal at the joint.

As the rocker 23 has the two flanges 100 24 each having only the single point of contact with the yoke and has a two point contact with the lid, it will be obvious that the rocker will automatically adjust itself, as the yoke is rotated, to compensate for any irregularity in the thickness of the rubber packing ring or in the jar and lid, the pressure being exerted equally upon opposite sides of the lid to clamp the same tightly upon the mouth of the jar. 110

The depending projections 7 upon the lower ends of the annular flanges 3 act as reverse stops to prevent the yoke from being turned beyond the disengaging position when the same is removed to open the jar. 115 These projections also permit of a considerable saving in time and labor in assembling the lids upon the jars for shipping, as the rubber rings may be placed inside of the jars, and the glass lid clamped directly upon the rim of the jar mouth, the L-flanges 18 of the yoke engaging the under sides of the depending projections 7, thus tightly clamping the glass lid upon the jar without the necessity of placing the rubber upon each 120 lid.

The provision of the glass lid, almost entirely exposed to view, permits inspection of the contents of the jar through the same, and the provision of the central shouldered 125 130

portion 11 upon the lid assists in quickly centering the same upon the mouth of the jar, and prevents the formation of an air pocket therein.

5 It is customary for a majority of housewives in canning fruit and vegetables, to invert each jar after the same is filled and sealed, in order to ascertain whether there is any leakage around the joint of the lid. Although it is claimed that the present invention provides a jar closure which assures a perfect seal, the yoke is preferably formed with a flat top, having an area sufficient to permit the jar to be inverted and stood upon its top, thus permitting the housewife to add here to custom in this regard.

I claim:

1. In combination with a jar having a pair of inclined, peripheral flanges around its neck portion; a closure including a lid arranged to compress a packing ring upon the mouth of the jar, a U-shaped yoke having L-shaped legs for engagement with the inclined, peripheral flanges, and a rocker member provided with two flanges each having a one-point contact with the yoke and said rocker member having a two-point contact with the lid.

2. In combination with a jar having a pair of inclined, peripheral flanges around its neck portion; a closure including a lid arranged to compress a packing ring upon the mouth of the jar, a U-shaped yoke having L-shaped legs for engagement with the inclined, peripheral flanges, and a rocker member provided with two flanges each having a one-point contact with the yoke and provided with a pair of knobs arranged to engage the lid at diametrically opposite points.

3. In combination with a jar having a pair of inclined, peripheral flanges around its neck portion, a closure including a lid arranged to compress a packing ring upon the mouth of the jar and having an annular groove in its upper face, a U-shaped yoke having L-shaped legs for engagement with

the inclined, peripheral flanges, and a rocker member provided with two flanges each having a one-point contact with the yoke and 50 provided with a pair of knobs arranged to engage the annular groove in the lid.

4. In combination with a jar having a pair of inclined, peripheral flanges around its neck portion, a closure including a lid 55 arranged to compress a packing ring upon the mouth of the jar, a U-shaped yoke having L-shaped legs for engagement with the inclined, peripheral flanges, and provided with a channel shaped body portion, and a 60 rocker member located in the channel body portion of the yoke and provided with a pair of knobs arranged to engage the lid at diametrically opposite points.

5. In combination with a jar having a 65 pair of inclined, peripheral flanges around its neck portion, a closure including a lid arranged to compress a packing ring upon the mouth of the jar, and having an annular groove in its upper face, a U-shaped yoke 70 having L-shaped legs for engagement with the inclined, peripheral flanges, and provided with a channel shaped body portion, and a rocker member located in the channel body portion of the yoke and provided with 75 a pair of knobs arranged to engage the annular groove in the lid.

6. In combination with a jar having a pair of inclined, peripheral flanges around its neck portion; a closure including a lid 80 arranged to compress a packing ring upon the mouth of the jar, a U-shaped yoke having L-shaped legs for engagement with the inclined, peripheral flanges, and a rocker member provided with two flanges each having a one-point contact with the yoke and provided with a pair of knobs arranged to engage the lid at diametrically opposite points, and means for preventing side ways displacement of the yoke. 85

In testimony that I claim the above, I have hereunto subscribed my name.

EDWARD A. DEWALD.
